UNITED STATES PATENT OFFICE.

HARRY SWINGLEHURST, OF PHILADELPHIA, PENNSYLVANIA, ASSIGNOR TO SCOTT & WILLIAMS, INCORPORATED, OF CAMDEN, NEW JERSEY, A CORPORATION OF NEW JERSEY.

SPEED-CHANGING AND STOPPING DEVICE FOR KNITTING-MACHINES.

1,116,161.

Specification of Letters Patent.

Patented Nov. 3, 1914.

Application filed July 13, 1912. Serial No. 709,880.

To all whom it may concern:

Be it known that I, HARRY SWINGLEHURST, a citizen of the United States, residing in Philadelphia, Pennsylvania, have invented certain Improvements in Speed-Changing and Stopping Devices for Knitting-Machines, of which the following is a specification.

The object of my invention is to provide efficient mechanism for stopping the operation of a knitting machine, and for automatically changing the speed of movement of the machine at a predetermined time or times. This object I attain in the manner hereinafter set forth, reference being had to the accompanying drawings, in which—

Figure 1 is a view, partly in side elevation and partly in section, of speed changing mechanism for knitting machines constructed in accordance with my invention; Fig. 2 is an end view looking in the direction of the arrow *x*, Fig. 1; Fig. 3 is a transverse section on the line *a—a*, Fig. 1, looking in the direction of the arrow *y*, and Fig. 4 is a transverse section on the line *c—c*, Fig. 1, looking in the direction of the arrow *w*.

In the drawing, 1 represents the supporting framework of the machine, and 2 the driving shaft which is mounted in suitable bearings in said framework 1 and in a bracket 3 projecting therefrom. Mounted upon and free to turn on the shaft 2 is a sleeve 4, and mounted upon and free to turn on the latter sleeve is another sleeve 5. To the sleeve 4 is secured a pulley 6 and to the sleeve 5 is secured a similar pulley 7, a third pulley 8 being secured directly to the shaft 2, as shown in Fig. 1. Secured to or forming part of the sleeve 4 is a spur pinion 9, which meshes with a spur wheel 10 which is free to turn on a stud 11 projecting from the frame 1. Secured to the inner side of the spur wheel 10 is a pinion 12, which meshes with a spur wheel 13, the latter being secured to a pulley 14 which is secured to the shaft 2. When the driving belt is upon the pulley 8 power will be imparted directly to the shaft 2 and the latter will be rotated at full speed. If, however, the belt 50 is shifted onto the adjacent pulley 6 power will then be transmitted to the shaft 2 through the medium of the shaft 4, spur

pinion 9, spur wheel 10, spur pinion 12, spur wheel 13, and pulley 14, and said spur gears and pinions are so proportioned as to reduce the speed at which the shaft 2 will then be rotated. The pulley 7 is a loose pulley and when the driving belt is shifted onto the same the transmission of power to the shaft 2 will cease and the movement of the machine will be arrested.

The above mechanism will be recognized as an instance of a well known form of power release and speed-changing gearing, as shown, for instance, in the patent to George D. Mayo, No. 726,178, dated April 21, 1903.

The belt shipper 15 is carried by a rod 16 suitably guided in a bearing 17 on the main frame, and said shipper has an arm 18 (Fig. 3) carrying a rod 19 which is guided in a bearing 20 on the bracket 3 so as to steady the shipper in its movements. The inner end of the shipper rod 16 carries a stud 21 which is adapted to the forked upper end of a shipper lever 22, the latter being pivotally mounted to provide a movable fulcrum at its lower end upon a slide 23 which can move to and fro upon a stud 24 projecting from the frame 1, the sleeve being prevented from turning on said stud by means of pins 25 projecting from said stud and entering slots 26 formed in the opposite sides of the sleeve, as shown in Fig. 4.

The shipper lever 22 has cheek pieces 27 disposed on opposite sides of an anti-friction roller 28 carried by the lower arm of a trip lever 29 which is pivotally mounted upon a stud 30 carried by a projecting bracket 31 on the frame 1, the upper arm of said lever 29 being pivotally connected to the outer end of a link 32 whose inner end has a projecting pin 33 which, when the trip lever 29 is in the position shown in Fig. 1 contacts with the hub 34 of a sector-shaped arm 35 secured to a short transverse shaft 36, which is adapted to a bearing projecting from the frame 1, this shaft also carrying the usual lever 37, whereby the stoppage of the machine by hand is effected. The upper face of the arm 35 is cam-shaped, as shown at 38, and engages with the bent lower end 39 of an upright shaft 40 which is mounted in a suitable bearing in the top of the sup-

porting frame 1 and is acted upon by the usual fabric or waste-detector actuated needle-protector or knock-off device of a knitting machine, such, for instance, as that shown in the patent to R. W. Scott and H. Swinglehurst No. 679,641, dated July 30, 1901.

A spring 41, coiled around the stud 30 and having an arm 41^a acting upon a boss 42 projecting from the lower end of the lever 29, tends to move said lever in the direction of the arrow, Fig. 1, but this movement is normally resisted by reason of the fact that the link 32 is normally held in the position shown in Fig. 1, because of its support by a lug 43 on the face of the arm 35. When, however, said arm 35 is depressed, either by the action of the knock-off shaft 40 or by the manipulation of the lever 37 the support of the lug 43 is removed from the link 32 and the latter is permitted to drop so as to carry its pin 33 below the hub 34 of the arm 35, and the lever 29 is then free to be moved by its spring 41 so as to turn upon its pivot stud 30 and, by engagement of the anti-friction roller 28 with the cheek pieces 27 of the shipper lever 22, move the latter so as to shift the driving belt from the pulley 8, or the pulley 6, which it may at the time be occupying, onto the loose pulley 7.

The means for operating the arm 35, and thus permitting the shifting of the belt through the medium of the trip lever 29, I term "emergency" devices, since they are not employed during the orderly operation of the machine. When, however, the shifting of the belt from one pulley to another has to be effected during such orderly operation of the machine the trip lever 29 remains locked in position on the stud 30, and the anti-friction roller 28 constitutes the fulcrum upon which the shipper lever 22 swings. Movement of this character is imparted to the shipper lever by means of a cam drum 45 which acts upon the sleeve 28 through the medium of a lever 46 and connecting rod 47, said lever 46 being pivotally mounted at one end upon a projecting lug 48 on the frame 1, and being pivotally connected at its opposite end to the rod 47, said lever carrying at an intermediate point a projecting pin 49 which engages with the cam slot in the drum 45, as shown in Fig. 1. The configuration of this cam slot will depend upon the shifting movements of the belt required at any particular time in the operation of the machine. If, for instance, the speed of movement of the machine is to be reduced at a certain point in the cycle of operations performed by the machine, say when the machine is changing from rotary to to-and-fro or reciprocating knitting, the configuration of the cam slot will be such as to impart a partial movement to the shipper lever 22 at such time so as to shift the belt

from the fast driving pulley 8 to the slow driving pulley 6, and if the machine is to be automatically stopped when it has completed its cycle of operations the formation of the cam slot will be such as to complete the 70 movement of the lever 22 at that time so as to shift the belt from the slow driving pulley 6 to the loose pulley 7.

Step by step movement of rotation is imparted to the drum 45 so as to complete one 75 revolution of the same during the performance of a complete cycle of operations by the machine, the means for effecting such operation being as follows: Secured to the drum 45 is a ratchet wheel 50, which is normally operated by a pawl 51 pivotally mounted upon one arm of a bell crank lever 52 whose other arm engages a pin 53 on a lever 54, vibrating movements being imparted to the latter by means of a cam on the 80 rotating cam cylinder of the machine, or in any other suitable way. The ratchet wheel 50 turns on a stud 55 of large diameter secured to the frame 1, and through this stud pass two shafts 56 and 57, the shaft 56 carrying, at its inner end, a pin-studded measuring wheel 58 (Fig. 1) which engages with the web of fabric produced by the machine and is turned by reason of such engagement with the web as the latter descends 85 on its way from the cylinder of the machine to the take-up mechanism below the wheel 58. The shaft 56 is geared by means of a spur wheel 59 and spur pinion 60 to the shaft 57, which carries a pattern chain drum 100 61, the pattern chain 62 having a lug 63, which, on each movement of the chain, strikes an arm 64 of a lever which is mounted so as to swing on a stud 65, and has another arm 66 carrying a plate 67 (Fig. 1) 105 which normally engages with the point of the pawl 51 and holds the same in position, where it is free from engagement with a low tooth 68 of the ratchet wheel 50 and consequently will not impart any movement to 110 the latter. When, however, the lug 63 strikes the lever arm 64 it will raise the same and therefore depress the arm 66 so as to permit the pawl to drop into engagement with the tooth 68 and start the movement 115 of the ratchet wheel, such movement being then continued by engagement of the pawl with the normal or high teeth of the wheel, the arm 66, when in its normal position, failing to prevent the engagement of the pawl with such normal or high teeth. A complete revolution of the ratchet wheel 50 and cam drum 55 will therefore be effected before the pawl 51 again drops into engagement 120 with the plate 67 on the arm 66 so as to be held out of engagement with the low tooth 68 of the ratchet wheel and thereby again arrest the movement of the same. Rotation of the ratchet wheel 50 is therefore effected only at periodic intervals determined by the 125 130

length of the pattern chain 62. Where several shifts from one speed to another may have to be made during the complete cycle of operation of the machine the ratchet wheel 50 may conveniently be provided with two or more low teeth 68 distributed around the periphery of the same.

The lever 37, whereby the arm 35 is operated by hand in order to effect the shifting of the belt from a fast pulley onto the loose pulley in order to stop the machine, carries a pin 70 which is intended to be connected to the take-up lever of the machine, so that in the event of any sudden drop of the latter, such, for instance, as might be caused by the web running off the needles of the machine, the lever 37 will be actuated so as to automatically stop the movement of the machine.

20 I make no claim to the mechanism whereby the cam drum 45 is operated in accordance with the orderly operation of the machine, as this has long been common except as an element of my new combination, and 25 I do not limit my present claim to mechanism of this character, as many equivalent devices could be used for the purpose, nor do I limit my broader claims to the particular emergency devices whereby the trip lever 30 20 is actuated, as these may also be modified without departing from the essential features of my invention.

The term "shipper lever" as employed in some of my claims does not necessarily mean 35 a lever for operating a belt shipper, since it is obvious that the releasing device could be one of the type employing a clutch and the speed train could be operated by other means than pulleys and a shifting belt.

40 I claim:

1. In a speed changing or stopping mechanism for knitting machines, the combination of a belt shipper, a shipper lever for actuating the same, having two fulcrums, a trip lever providing one of said fulcrums, emergency devices for releasing said trip lever, cam mechanism moving in accordance with the orderly operation of the machine, and mechanism whereby said cam mechanism is 50 connected to the other fulcrum of the shipper lever.

2. In speed changing or stopping mechanism for knitting machines, the combination of a shipper lever, a trip lever on which 55 said shipper lever is fulcrumed, emergency stop mechanism for controlling the position of said trip lever, cam mechanism moving in accordance with the orderly operation of the machine, and mechanism whereby the

60 shipper lever is under control of said cam mechanism, whereby the shifting of the belt may be effected either by said cam mechanism or by the operation of the trip lever.

3. In speed changing or stopping mechanism for knitting machines, the combination

of a shipper lever having cheek pieces thereon, a trip lever having a member projecting between said cheek pieces and constituting a fulcrum for the shipper lever, cam mechanism moving in accordance with the orderly 70 operation of the machine, and means whereby said cam mechanism is caused to operate the shipper lever upon the before-mentioned fulcrum.

4. In speed changing or stopping mechanism for knitting machines, the combination of the shipper lever, a trip lever on which the same is fulcrumed, a slide having pivotal connection with said shipper lever, cam mechanism moving in accordance with the orderly 75 operation of the machine, and means whereby said cam mechanism is caused to operate said slide, whereby the shipper lever may be caused by the movement of the slide to swing upon its fulcrum on the trip lever, or be caused by the movement of the trip lever to swing upon its fulcrum on the slide.

5. In a power release and control mechanism for knitting machines, emergency actuated devices, pattern controlled devices, a power-release and speed changing drive gearing, shipper means for controlling the release and speed change, and a lever connected at one end to said shipper means, at 90 the other to one of said devices, and in the middle to the other of said devices, whereby by the shipper means may be independently actuated by either of said devices.

6. In a knitting machine, a variable speed 100 mechanism, an emergency stop motion mechanism comprising a power release device, a shipper lever for moving the release device, capable in one position of shifting the drive from one speed to another speed, said shipper lever having a movable fulcrum, a spring actuated lever providing at one end a free bearing for said shipper lever, and means for releasing the spring 105 actuated lever, in combination with pattern controlled means for moving the fulcrum to independently control the position of the belt shipper to vary the speed.

7. In a knitting machine, emergency 11 actuated stop motion mechanism comprising a power release device, a shipper lever for moving the release device, having a movable fulcrum, a spring actuated lever providing at one end a free bearing for said shipper lever, and means for releasing the spring 120 actuated lever, in combination with pattern controlled means for moving the fulcrum to independently control the position of the release device.

8. In a stop motion device for knitting 125 machines, the combination of a shipper lever having two fulcrums, a trip lever carrying one of said fulcrums and having a locking link, means tending to move the trip lever to operate the shipper lever, a rock shaft carry-

ing both a hand lever and an arm provided with a lug which normally holds the link in locking position but which when withdrawn permits said link to remove to a releasing position, and emergency devices for operating said hand lever.

In testimony whereof, I have signed my

name to this specification, in the presence of two subscribing witnesses.

HARRY SWINGLEHURST.
